UNITED STATES PATENT OFFICE

WALTER WANDERWELL, OF MIAMI, FLORIDA

DESIGN FOR AN AUTOMOBILE

Application filed February 3, 1931. Serial No. 38,536. Term of patent 14 years.

To all whom it may concern:

Be it known that I, WALTER WANDERWELL, a citizen of the Republic of Poland, residing at Miami, in the county of Dade and State of Florida, have invented a certain new, original, and ornamental Design for an Automobile, of which the following is a specification, reference being had to the accompanying drawing, forming a part thereof.

The figure in the drawing is a partial side and partial rear perspective view of the rear portion of the body, showing by dotted lines other portions of the body and vehicle.

I claim:

The ornamental design for an automobile as shown.

In testimony whereof, I have hereunto set my hand at New Orleans, Louisiana, this 19th day of January, 1931.

WALTER WANDERWELL.
